(57) **CLAIM**

The ornamental design for an oblong CD case, as shown and described.

DESCRIPTION

FIG. 1 is a perspective view showing the oblong CD case embodying my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a perspective view showing the oblong CD case in an open configuration.

The broken lines shown throughout the views are understood to represent stitching.
